UNITED STATES PATENT OFFICE.

JOSEPH G. JOHNSTON, OF DETROIT, MICHIGAN, ASSIGNOR TO THE AMERICAN CAR & FOUNDRY COMPANY, OF ST. LOUIS, MISSOURI.

WHEEL-MOLDING APPARATUS.

SPECIFICATION forming part of Letters Patent No. 672,778, dated April 23, 1901.

Application filed July 9, 1900. Serial No. 22,987. (No model.)

To all whom it may concern:

Be it known that I, JOSEPH G. JOHNSTON, a citizen of the United States, residing at the city of Detroit, county of Wayne, State of Michigan, have invented a certain new and useful Improvement in Wheel-Molding Apparatus, of which the following is a full, clear, and exact description, such as will enable others skilled in the art to which it appertains to make and use the same, reference being had to the accompanying drawings, forming part of this specification, in which—

Figure 1 is a top plan view of my improved wheel-molding machine. Fig. 2 is a side elevational view of the same. Fig. 3 is a plan view of the drag or nowel pattern. Fig. 4 is a sectional view on line 4 4, Fig. 1. Fig. 5 is a top plan view of the cope-pattern, the matrix skeleton frame and chill-ring being partly broken away. Fig. 6 is a vertical sectional view on line 6 6, Fig. 5. Fig. 7 shows the drag-matrix in position on the nowel side of the wheel, the same being illustrated as broken at its middle portion and showing the right and left halves of the same in their relative positions to the pattern, respectively, before and after said drag-matrix has been subjected to pressure, the pattern still being in place. Fig. 8 shows the drag-matrix in proper position—that is, inverted with respect to the positions shown in Figs. 4 and 7—the pattern being withdrawn in Fig. 8. Fig. 9 shows the cope placed in position on the nowel, the two sides of the flask being secured together and the wheel formed therein. Fig. 10 illustrates the assembled flasks in elevation, showing the manner of securing them together; and Fig. 11 is a plan view of the sand-supply spout and its controlling gate or damper employed in carrying out my invention.

This invention relates to a new and useful improvement in wheel-molding machines, the same being designed for use particularly in the formation and manipulation of patterns and molds used in connection with making castings of car-wheels.

The object of my present invention is to provide a machine of the character described for packing the sand around the pattern and

forming the different molds or matrices, which are afterward pointed up or finished by hand and assembled to receive the molten metal. In this way considerable manual labor is saved in the tamping of the sand around the patterns, in addition to which a firm and uniform matrix is provided, which matrix will yield a good casting.

The invention consists in arranging a turnet or turn-table, on which the patterns are placed, said patterns coöperating with the skeleton flasks to receive the sand, a preferably-stationary sweep being provided for distributing sand evenly and of uniform depth over the pattern and in the spaces of the skeleton flask. Where such a flask is used, means are provided to lift the pattern and simultaneously rotate the same under said stationary sweep. A hydraulic or other press coöperates with the pattern to compress the sand therebetween, thus fixing the impression and rendering the mold firm, so that it may be handled without fear of its being broken.

In the drawings, A indicates a turn-table, to the under side of the periphery of which is secured a circular rack a, designed to mesh with a driving-pinion, (not shown,) whereby said table may be rotated. This table is supported on a suitable stand B.

C and C' indicate girders arranged above and below the table, their inner ends being received by suitable yokes, which are connected together through the medium of the pivot-rod c for the table, while corresponding yokes coöperate with the outer ends of said girders and are connected by vertical rods c' or posts, as shown. This structure forms a strong frame, within which is included a hydraulic or other press, comprising a cylinder D, supported by girders C', whose ram d is designed to pass through an opening in the turn-table A and compress the sand between one of the patterns carried by said turn-table and a dead-plate E, carried by the girders C. Suitable pipe connections provided with throttle or controlling valves lead from some suitable source of hydraulic-pump compressed-air or steam supply, whereby the ram may be raised or lowered, as desired.

F indicates a counter-shaft on which are

arranged fixed and loose pulleys over which a driving-belt passes. This shaft through suitable miter-gearing drives a vertical hollow shaft G, mounted upon a piston-rod, which piston-rod is connected to a plunger arranged in cylinder H. The miter-gear of shaft G is mounted on a key or feather, so as to permit the vertical movement of said shaft without disturbing the mesh of said gear with its driver. The upper end of shaft G carries a plate I, on whose upper face are arranged two or more centering pins or projections i, designed to be received by a pattern K or O when said plate is elevated for the purpose of centering said pattern and when said plate is rotated to carry said pattern with it. The wheel-patterns K and O are each provided with a central boss or panel K' O', respectively, which fits into an opening in the turn-table A for definitely locating said patterns with respect to the table. Suitable pipe connections lead from some source of compressed air or steam supply and are controlled by valves for admitting pressure beneath or above the plunger in cylinder H for accomplishing the vertical movement thereof and its connected plate I. As the plunger in the cylinder is usually packed, I prefer to so construct the parts that the plate I may be rotated while the plunger and its piston-rod remain stationary. This can be accomplished by providing the lower end of shaft G with an opening or socket for receiving the piston-rod h and slidingly mounting the miter-gear g on this shaft G.

Referring now to Fig. 4, it will be seen that plate I has been elevated so as to lift the pattern from the table, which pattern, we will mention incidentally, is here shown as a drag, and when the pattern is so elevated and rotated it occupies a position under a fixed or stationary sweep J. This sweep is preferably secured to a sand-supply spout J', which is provided with a segmental opening closed by a gate j, pivoted at the junction of the converging lines thereof, said gate having a radial opening edge to permit the proper volume of sand to fall onto the pattern. When the pattern is rotated, the gate is opened to discharge a proper quantity of sand onto said pattern, which sand is immediately spread out and distributed uniformly over the pattern by the sweep J. The proper quantity of sand having been placed on the pattern and distributed, as above described, the surplusage is removed, the pattern arrested, and again deposited on the turn-table.

By reference to Fig. 1 it will be seen that the turn-table is provided with four openings, and therefore carries four patterns practically at all times. After passing from the rotating plate I the pattern, covered by sand, receives the flask and is ready to be operated upon by the hydraulic press. When the flask is being introduced on the pattern, another pattern is receiving its sand. When said other

pattern has been properly manipulated and the turn-table again operated so as to be rotated one-fourth of a revolution, the second pattern is in readiness to receive its flask and the first pattern is placed in position over the ram of the press. Pressure is now admitted under the plunger of cylinder D and the pattern elevated until its flask is brought into contact with the dead-plate E, when the sand between the pattern and the flask is subjected to sufficient pressure to make a firm mold. The ram is now permitted to descend and the pattern is again supported upon the turn-table A. During this pressing operation the third pattern has received its sand and the second pattern has received its flask. The third movement of the table carries the first pattern, with its compressed sand and flask, away from the ram and places the second pattern, with its flask, in position to be subjected to pressure, the third pattern in position to receive its flask, and the fourth pattern in position to receive its sand. All the patterns operated upon are provided with suitable trunnions, as are also their coöperating flasks. The pattern which we have designated the "first" pattern and its flask with the sand compressed between them are now clamped together and lifted from the table by a suitable bail (not shown, but which is preferably operated by an air-hoist) and when suspended in the air is turned in its bail so that the flask will be underneath. The flask is now deposited on a suitable arrangement for supporting the mold from the pattern, and the pattern when so separated is replaced in the opening in the turn-table A which it recently vacated.

The above description applies to the drag side of the mold, and while I have described a turn-table provided with four openings, attributing four different operations to as many different positions of the table, it is obvious that the turn-table could have a greater number of openings, in which event there would be given a longer time between the pressing and resanding operations. For instance, were the turn-table provided with five openings the sanding operation would be succeeded by the placing in position of the flask at the first interval of rest. The second interval of rest would be consumed by the pressing operation and the third and fourth intervals in the removal and separation of the pattern from its flask and the replacement in position of the pattern, the fifth interval being occupied by the resanding operation.

I will now describe the novel details of construction of my improved patterns, both drag and cope, and their associate parts.

K indicates the drag-pattern, consisting of a casting, which is cored out for the purpose of making the same light, said casting consisting of an imperforate face-plate shaped to the contour of one surface of the wheel to be cast. This face-plate is provided with ribs

k, which make impressions for the strengthening-braces of the wheel. *k'* indicates a removable core-print. This core-print is removable in the sense that different-sized cores are used with the same pattern, the change in the size of the prints being made as occasion demands. While in use the print is firmly secured to the pattern and has a sufficient draft to enable it to be lifted out of the sand with the pattern. These remarks apply also to core-print cope-patterns. The above is the usual method and may be followed; but I prefer in order to save time in setting the core so that it will be in exact position in its relation to other parts of the mold that a core-print *x* be made in the drag-pattern to admit of the axle-core being placed therein. Bushings may be employed to enlarge or reduce the diameter of the opening, so that various size cores may be used. The core when in place will project above the pattern, so that when the mold is pressed and turned over the core, being of proper length and firmly seated in the mold, will render a print on the cope side of the mold unnecessary. The pattern is surrounded by a circumferential flange *k*² for containing the sand. *k*³ indicates webs on the under side of the face-plate and attached to the bottom wall *k*⁴, which bottom wall is connected by a circumferential flange to the face-plate. A supporting-flange *k*⁵ extends horizontally from the face-plate and is provided with a finished rib at its inner edge, designed to bear upon the turn-table. Radially-arranged strengthening-webs support the face-plate above this flange for the purpose of giving strength to the same, while the pattern-ribs *k*⁶ also strengthen the pattern. This construction makes a very rigid pattern and one well able to resist the strain to which it is subjected when in the press.

As shown in Fig. 4, the stationary sweep *J* surfaces the loose sand to correspond with the contour of the face-plate of the pattern, and when the pattern is swung around by the turn-table from its position over the rotary plate *I* a flask or backing *L* is loosely placed in position on the surfaced sand. This flask or backing-plate is shown in Fig. 5 and consists of a circumferential flange *l*, whose inner edge is beveled or formed knife-like and of such diameter as to fit within the circumferential flange of the pattern *K*. The supporting-plate *l'* is shaped to the contour of the sand over which it is placed, said plate being preferably provided with perforations to permit the gas which is formed by the meeting of the molten metal and the sand to readily escape. The plate is further strengthened by skeleton webs or braces, which are both radially and concentrically arranged, as shown at the bottom of Fig. 1. After this flask is placed in position, the knife-edges fitting within the circumferential flange of the pattern, the pattern is placed upon the ram of the press, which elevates it and its carried parts until the flask comes in contact with the

dead-plate. The circumferential flange and the strengthening-ribs of the flask rest on a horizontal plane, so as to distribute the stress in compressing the sand evenly throughout the whole structure, and this compressive action is carried on until arrested by the flange of the flask contacting with the face-plate of the pattern. (See right-hand side of Fig. 7.) Of course the proper quantity of sand is introduced, so that when the flask and pattern are forced together to this extent the sand is compressed to the desired degree of firmness. Both the pattern and the flask are provided with trunnions *k*⁷ and *l*⁸, respectively, for co-operating with the bail of an air-hoist. Lugs or ears may be provided on the flask and pattern, whereby the same may be secured together when under pressure to prevent displacement of either of said parts during the act of inverting them to get the flask on the under side and make accessible the pattern for purposes of withdrawal. Lugs or ears *k*⁹, Fig. 3, preferably have fixed dowel-pins, which enter holes in corresponding lugs or ears on the drag *L*. (See Fig. 10.) When the mold is being pressed, the pins center the flask, and when the pattern and flask are clamped together the pins keep them in position while being turned over.

As shown in Fig. 9, the chill rests upon the knife-edge of the flask *L*, and thus makes a parting at the crown of the wheel-flange, the chill-ring, which I have marked *M*, being co-extensive with the throat and tread of the wheel. This chill-ring is provided with trunnions *m*, by which the same may be handled by the bail or hoist, and is also provided with lugs or ears *m'* for receiving securing-clamps for attachment to the flask *L*.

N indicates a skeleton flask which is bolted or otherwise secured to the chill-ring, said flask, as shown in Figs. 5 and 6, being of skeleton form and having the inner edges of its concentric and radial ribs beveled or formed with knife-edges to enable the sand to pack therebeneath. The skeleton cope-flask is so made that it conforms to the contour of the pattern both as to the sharp edges of the bars next the pattern and the edges next the dead or backing plate.

In operation the "cope" and "chill," as they are called, being secured together are placed over a pattern *O*, which pattern shapes the mold of the cope for the face of the wheel. This pattern consists of a face-plate *o*, properly shaped, in the center of which is arranged a removable core-print *o'*. The face-plate is strengthened on its lower side by suitable strengthening webs or ribs *o*² and has a bottom plate *o*³, forming a reduced portion, fitting in the opening of the turn-table *A*, said bottom plate being perforated for the centering-lugs of the rotary plate *I*.

*o*⁴ indicates spring-seats projecting laterally from the pattern, four of such seats being preferably arranged equidistantly around the pattern. Springs *o*⁵ are arranged in these seats

and sustain an inverted cup or cap-piece o^6 , serving as a follower and guide, and also supporting the chill-ring M . Bolts o^7 , passing through the cap-piece and spring-seat, hold the spring under compression and limit the upward movement of the caps. The chill rests upon the spring-caps, and the bolts are used to adjust the springs to a uniform height, so that the bars of the cope will at all points be uniformly distant from the pattern, the springs being of sufficient strength to support the chill-ring, skeleton cope, and sand without being further compressed. In addition to the springs the cope-pattern is provided with two lugs or ears, and in these are fixed pins which enter holes in the lugs m' on the chill-ring, as shown in Fig. 10. The fixed pins in the lugs on the cope and drag patterns have corresponding centers, so that when the two parts are brought together the mold will be perfect. The cope-pattern is further provided with stops which meet the face of the chill-ring when the mold is being pressed, making a uniform distance of travel for the pattern in its upward motion.

In operation, the pattern being in position on the turn-table, the cope and chill are arranged thereon, their weight being supported by the springs. The springs are adjusted so that they support the combined weight of skeleton flask, chill-ring, and sand without further compression, so that the skeleton flask occupies a definite position above the pattern. The table now makes a one-quarter turn and the pattern, with flask, is elevated to receive the sand, which is distributed uniformly over the pattern by a sweep conforming to the shape of the pattern. This operation is substantially the same as that described with reference to the distribution of sand on the drag side. When the pattern, with the chill-ring and cope and with the sand distributed thereover, occupies a position over the press, the ram will raise the pattern, chill-ring, cope, and sand, which latter are solely supported by the springs on the pattern. The outer ring of the skeleton cope-flask is fixed on both sides, so as to make uniform molds. In the upward movement of the pattern and its carried flask the latter contacts with the dead-plate E , the springs are compressed, and the pattern forces the sand upward against the beveled edges of the bars in the cope and against the backing-plate, thus making a perfect mold. Upon the pressure being released the pattern travels downward and the compression of the springs is utilized to separate the pattern from the sand, while the combined flask and pattern settle downwardly until they rest upon the table. The table now makes one quarter-turn, and by a suitable bail the chill-ring and skeleton flask, with the sand compressed therein, is lifted from the table, and when pointed up, if such be necessary, and blacking put on, is ready to place over the corresponding drag side of the mold. This

part of the mold is commonly known as the "cope" side of the mold, and pouring-gates are formed in the hub of the cope side of the mold by fixed pins in the cope-pattern, the sand being pressed around the pins when the mold is being formed. When the drag side of the mold has been removed from the table, inverted, and the pattern drawn, the mold is pointed up, if necessary, and blacking put on, and the concentric core U is placed in position to form a concentric opening around the hub of the wheel. The concentric cores have projections or feet u on the under side, which rest in corresponding depressions in the mold formed by prints on the pattern when the mold is being pressed. The core is prevented from rising or floating by chocks u' , placed in the ordinary manner. The axle-core V is then placed in position, if not already in position, having been rammed up in the mold. The casting is represented at W in Fig. 9. The two parts of the mold, which are known as the "cope" and "drag," being complete, the cope is placed over the drag and the two clamped together and are kept in relative position by loose closely-fitting pins passing through the corresponding lugs on the chill-ring and drag-flask. A bowl or pouring-head is placed over the gates in the usual manner, and the mold is ready to receive the molten metal.

While I have seen fit to describe to an extent the construction of the drag-pattern and flask and the cope-pattern and flask in this application for the purpose of rendering the operation of my improved machine more comprehensive, I make no claim herein to these constructions, as they are subjects-matter of separate applications filed by me December 13, 1900, and serially numbered 39,693 and 39,691, respectively.

I am aware that minor changes in the arrangement, construction, and combination of the several parts of my device can be made and substituted for those herein shown and described without in the least departing from the nature and principle of my invention.

Having thus described my invention, what I claim, and desire to secure by Letters Patent, is—

1. In a molding-machine, the combination with a turn-table carrying a plurality of patterns, of mechanisms for coöperating with one of said patterns on said turn-table to lift the same therefrom, means for rotating said pattern when the same is in its elevated position, and a sweep designed to coöperate with and give shape to, sand which is contained in said pattern when the same is being rotated; substantially as described.

2. In a molding-machine, the combination with a turn-table carrying a plurality of patterns, of a rotatable plate designed to register with any one of the plurality of patterns carried by said turn-table by the proper manipulation of the latter, means for moving said rotatable plate vertically to lift one of said

patterns from said turn-table, means for rotating said rotatable plate and pattern in their elevated position, and a sweep for giving shape to the sand which is contained in said patterns; substantially as described.

3. The combination with a turn-table provided with openings, of patterns seated in said openings, a rotatable plate arranged under the table, and with which the patterns register in their revolution, means for elevating said plate to lift a pattern from the table, mechanism for rotating the elevated plate and its carried pattern, and a stationary sweep for giving shape to the sand on the pattern; substantially as described.

4. The combination with a turn-table provided with openings, of patterns seated in said openings, a rotatable plate so arranged as to register with said patterns at a point in their revolution with said turn-table, means for lifting and rotating said rotatable plate and its carried pattern, a sweep for giving shape to the sand carried in said pattern, a flask carried by said pattern and designed to rest upon the sand contained in said pattern, and a press for compressing said sand between

said pattern and flask; substantially as described.

5. The combination with a turn-table provided with openings, of patterns arranged on said turn-table over said openings, flasks on the patterns, girders above and below the turn-table, posts connecting said girders, a cylinder on the lower girders, a piston in the cylinder, a ram carried by said piston which is designed to pass through the openings in the table, and a dead-plate arranged under the upper girders, whereby, when the piston and its carried ram is caused to ascend, the ram engages the pattern by passing through the opening in the table, and lifts said pattern and its carried flask, forcing the flask against the dead-plate; substantially as described.

In testimony whereof I hereunto affix my signature, in the presence of two witnesses, this 29th day of June, 1900.

JOSEPH G. JOHNSTON.
